UNITED STATES PATENT OFFICE.

WALTER MACLEOD, OF CINCINNATI, OHIO.

FURNACE FOR MELTING METALS.

1,312,129.

Specification of Letters Patent.

Patented Aug. 5, 1919.

Application filed December 2, 1916. Serial No. 134,751.

To all whom it may concern:

Be it known that I, WALTER MACLEOD, a citizen of the United States, residing at the city of Cincinnati, in the county of Hamilton and State of Ohio, have invented certain new and useful Improvements in Furnaces for Melting Metals, of which the following is a specification.

The object of my invention is to produce a furnace for melting metals formed of two separate chambers, one being the furnace proper for producing the heat units or heat waves and the other being the melting pot; the heat produced in the furnace chamber being forced to travel through a duct into the melting pot. In this way I obviate the necessity of using a crucible made of plumbago or equivalent refractory material, and directly heated.

The features and advantages of my invention will readily become apparent from the following specification and claims.

In the accompanying drawing forming part of this specification:

Figure 1, is a side elevation of my new improved furnace for melting metals,

Fig. 2, is an end elevation thereof, and

Fig. 3, is a sectional view, taken on the line 3—3 of Fig. 2.

The furnace, in the present instance, is supported on a frame work or base 1, made of suitable material. The furnace proper, which contains one chamber and in which the air or other products are heated, is marked 2 and the other chamber, which forms the melting pot, is marked 3.

The part 3 which forms the melting pot also carries the duct 6 through which the heated air waves or heat units pass. At the meeting point between these two parts or sections 2 and 3, at 13, I form a "jump joint", to enable the tilting of the melting pot. In furnace part 2 I provide a pocket or chamber 8 and in the melting pot or part 3 I place the pocket or chamber 10.

The furnace 2 is made up of fire brick or equivalent material 4, and the melting pot 3 of the same material, which is marked 5. The duct 6 is surrounded by fire brick or equivalent material 7.

In the furnace part 2 I form a chamber or air pocket 8, which may be of any size, a short conveyer duct 9 passing therefrom to the duct 6 with which it forms a connecting continuous passageway for hot air

or heat waves or units. In this manner the chamber 8 is connected to the pocket or chamber 10 in the melting pot 3.

The whole fire brick material is surrounded with a retaining and supporting element 12.

The pocket or chamber 8 is provided with a conveyer duct 14 leading therefrom and connecting with an air or blow pipe 15, through which air is blown or forced into 65 and through the chamber 8, through duct 9 and through duct 6 into the chamber 10 of the melting pot 3.

Under the furnace part 2 I provide a burner 16 of any approved form, in the present instance having handle connections 17 and 18 and 19, for gas, oil and air respectively, so that either gas or oil may be used and air provided for better combustion. This burner heats the furnace and the chamber 75 8 to any desired degree of heat. The burner may extend up to chamber 8 if desired.

The chamber 10 of the melting pot 3 is provided with a lid or cover 20 of any suitable construction. In the present instance the lid is provided with ring 21 to which is attached the chain 22, this chain being also connected to handle 23 through agency of short arm 24. The handle is connected to 85 top of furnace part 2 at the point 25. Through the medium of an eccentric connection 26 and pin 27, (shown in dotted lines), the movement of the handle raises the lid and it can be swung out of the way. 90 This is all that need be said about the cover raising means, as any device may be used for raising the cover of the melting pot.

In order to tilt the melting pot I use the following construction.

The melting pot 3 is supported in bearings 28 on short shaft 29, (one at each side) in which it swings in order to be tilted. On one of the shafts 29 I provide a spiral gear 30, which meshes with worm gear 31, the 100 worm gear being carried in brackets 32 through which the shaft 33 passes. On this shaft 33 I place a miter gear 34 which meshes with miter gear 35 supported in the bearings 36. The miter gear 35 is on a shaft 105 37 and at the extremity of this shaft I place a hand wheel 38.

By turning the hand wheel 38 motion is imparted to the shaft 37 which turns gear 35 which in turn revolves gear 34 on the 110

shaft 33; the shaft 33 turning with worm gear 31 revolves spiral gear 30, which, being fast on shafts 29 operates said shafts, which operation tilts the melting pot 3, the 5 molten metal pouring out of chamber 10 over spout or lip 39. When the melting pot is tilted the parts break at the jump joint 13.

The chambers in the parts 2 and 3 may be of any size or contour and communicatively connected in any manner found desirable.

I may use any approved means for forcing air into the hot air chamber 8 and forcing it therefrom.

15 It will readily be understood that by providing two separate chambers, one for producing the heat and the other for melting the metal, by forcing heat waves from the heating chamber to the chamber holding the 20 metal, I form a unique and efficient apparatus for metal melting and do not need plumbago in crucible form for producing the result sought to be attained. Plumbago and other peculiar refractory materials can 25 not always be obtained when wanted so I attain the same results as a crucible of this character in my new metal melting furnace.

What I claim as new and my invention and desire to secure by Letters Patent is:

30 1. In a furnace for melting metal, two separate sections, one having a chamber for producing heat and the other having a chamber for melting the metal, a passage way leading into the heat producing chamber 35 from below, a passage way extending between the chambers for transmitting the heat waves for melting the metal, a burner under the heating chamber arranged so that the flames will pass up into the heating

chamber, a passage way from the heating 40 chamber extending to the outside thereof for the intake of air to produce intensity of heat and quicken the heat waves through said passage way into the melting chamber, said air intake approximately in the same horizontal 45 line as the passage way to the melting chamber, a jump joint between said heating chamber and melting chamber, and means for tilting the melting chamber.

2. In a furnace for melting metal, two separate sections, one having a chamber for producing heat and the other having a chamber for melting the metal, a passage way leading into the heat producing chamber from below, a passage way extending between the 55 chambers for transmitting the heat waves for melting the metal, a burner under the heating chamber arranged so that the flames will pass up into the heating chamber, a passage way from the heating chamber extending to the outside thereof for the intake of air to produce intensity of heat and quicken the heat waves through said passage way into the melting chamber, said air intake approximately in the same horizontal 60 line as the passage way to the melting chamber, a jump joint between said heating chamber and melting chamber, and means for tilting the melting chamber, said chambers made of a hard brick or clay and surrounded by an iron jacket.

Witness my hand at Cincinnati Ohio, November 29th 1916.

WALTER MACLEOD.
